BURIAL VAULT

William Jack Greenway Kirkpatrick, Islington,
Ontario, Canada

Application June 3, 1947, Serial No. 139,418

Term of patent 3½ years

(Cl. D19—1)

To all whom it may concern:

Be it known that I, William Jack Greenway Kirkpatrick, a citizen of the Dominion of Canada, residing at Burnhamthorpe Road, R. R. 1, Islington, Province of Ontario, Canada, have invented a new, original, and ornamental Design for Burial Vault, of which the following is a specification, reference being had to the accompanying drawings, forming part thereof, in which

The figure is a front perspective view of the burial vault showing my new design. The end of the burial vault which is not shown in the drawing is the same as the end which is shown. The rear side which is not shown is the same as the front with the wing and sphere ornament omitted.

I claim:

The ornamental design for a burial vault, as shown and described.
WILLIAM JACK GREENWAY KIRKPATRICK.
